UNITED STATES PATENT OFFICE

NIELS C. NIELSEN, OF KANSAS CITY, MISSOURI.

SERVICE-BOX COVER.

1,199,811.

Specification of Letters Patent.

Patented Oct. 3, 1916.

Application filed April 13, 1914. Serial No. 831,428.

To all whom it may concern:

Be it known that I, NIELS C. NIELSEN, a citizen of the United States, residing at Kansas City, in the county of Jackson and 5 State of Missouri, have invented certain new and useful Improvements in Service-Box Covers, of which the following is a full, clear, and exact description, such as will enable others skilled in the art to which 10 it appertains to make and use the same.

The invention relates to covers for service boxes and seeks to provide a simple and effective form of cover which may be secured to the box without the aid of bolts 15 or separable parts.

Service boxes are employed as a means of communication with the stop cock which is usually under ground near the street curb, for the purpose of cutting off and turning 20 on the supply of water or gas served to the consumer.

Service box covers are used to close the upper end of the box which is near or at the surface of the ground, and the cover 25 must be removed to shut off or turn on the supply of water or gas; also the cover must be replaced after each manipulation of the stop cock. It is usual to secure the cover with a bolt or bolts which become tight 30 from rust or corrosion and often break on an attempt at removal. The removal often requires drilling and considerable time besides the expense of renewal.

The present invention seeks to provide an 35 improved service box cover which may be readily secured to or removed from the service box by the aid of a special wrench provided for the purpose.

By constructing the cover for manipulation only by a special wrench, the removal 40 of the cover by those not having the authority is prevented.

A further object of the invention is to provide means on the upper end of the box, 45 and companion means on the cover to prevent water from entering the box.

With these and other objects in view, the invention consists in the features of construction, combinations and arrangements 50 of parts hereinafter set forth, illustrated in the accompanying drawings and more fully pointed out in the claims appended.

Figure 1 is a view in elevation of a service box to which the improved cover is applied. Fig. 2 is a view in vertical section 55

of the box and cover taken on line a—a of Fig. 3. Fig. 3 is a plan view of the service box and of the cover. Fig. 4 is a plan view of the service box with the cover removed. Fig. 5 is a view in elevation of the improved cover. Fig. 6 is an inverted plan view of the cover.

Above the stop cock 1 and centrally located therewith is the lower section 2 of the service box, which is provided with flange 60 3 to serve as a rest and with external thread 4, the latter being cast integral with the section, it being considered too expensive to machine threads on a service box.

The upper section 5 of the service box has 70 internal thread 6 from end to end which is cast integral with the section, and serves to lengthen and shorten the box and as a means of securing the cover 7. It is obvious that thread 6 may be only in both 75 ends of the section 5 and may not necessarily run from end to end. The upper end of section 5 is provided with radial flange 8 and annular flange 9.

Cover 7 is provided with external thread 80 11 cast integral therewith and fitting the internal thread 6 of section 5, and secured thereto by the locking of thread 11 in thread 6. Cover 7 is provided with radial flange 12 extending outwardly, from which 85 annular flange 13 extends downward so that when the cover is screwed in place as in Figs. 1 and 2, flange 12 of the cover rests on flange 9 of section 5, while flange 13 of the cover rests on flange 8 of section 5. It 90 will be understood from the foregoing that no water can run under the cover 7 and into section 5.

Cover 7 is provided with hole 14 having 95 5 flat sides to which a special wrench is fitted to secure it to section 5 or remove it therefrom so that the cover cannot be removed by an ordinary wrench or flat bar, it being desired to prevent opening of the cover except by those having authority as 100 water and gas is not usually turned on or off by the consumer.

The cover 7 and upper section 5 are ready 105 for use when they leave the foundry and require no bolts or separable parts to secure them together. It is the work of but a moment to close or open the box with a special wrench and reasonable security is afforded thereby against those not in authority manipulating the cover or the cock 110

1; while the service box covers now in use are expensive both to manipulate and to maintain and do not afford the same degree of security.

5 Having described my invention, what I claim as new and desire to secure by Letters Patent, is:—

10 1. In service stop boxes the combination of, a tube, an annular flange integral with the bottom of said tube, said flange adapted to be placed over a stop cock of a water pipe below the surface of the ground, threads on said tube, a sleeve, threads in said sleeve and adapted to fit said threads 15 on said tube, the outer surface of said sleeve being cylindrically smooth, a cover, threads on said cover and adapted to screw in said threads in said sleeve, and an annular flange on said cover adapted to fit

over the end of said sleeve when said cover 20 is screwed on said sleeve.

2. In service stop boxes the combination of, a tube, an annular flange integral with 25 said tube, adapted to fit over a stop cock of a water pipe, a sleeve, fitting over and around said tube, the outer surface of said sleeve being cylindrically smooth, a cover closing the end of said sleeve, and a single means by which the distance of said cover from said tube may be adjusted and said 30 cover secured to said sleeve.

In testimony whereof I affix my signature in the presence of two witnesses.

NIELS C. NIELSEN.
